United States Patent Office

Des. 199,698
Patented Dec. 1, 1964

199,698

BOTTLE

Donald E. Dailey, Evansville, Ind., assignor to John H. Breck, Inc., Springfield, Mass.

Filed Oct. 11, 1962, Ser. No. 72,077

Term of patent 14 years

(Cl. D58—6)

Fig. 1.

FIG. 1

FIG. 1 is a view in perspective of a bottle embodying my novel design; and

FIGS. 2 and 3 are side and end elevational views, respectively of the bottle of FIG. 1.

I claim:

The ornamental design for a bottle, as shown.
